UNITED STATES PATENT OFFICE.

HARRY N. MARVIN, OF CANASTOTA, NEW YORK, ASSIGNOR, BY MESNE ASSIGNMENTS,
TO BIOGRAPH COMPANY, OF NEW YORK, N. Y., A CORPORATION OF NEW JERSEY.

ANIMATED-PICTURE APPARATUS.

1,021,060.

Specification of Letters Patent. Patented Mar. 26, 1912.

Application filed March 7, 1904. Serial No. 196,820.

To all whom it may concern:

Be it known that I, HARRY N. MARVIN, a citizen of the United States, residing at Canastota, in the county of Madison and State of New York, have invented certain new and useful Improvements in Animated-Picture Apparatus, of which the following is a specification, reference being had to the drawing accompanying and forming part of the same.

My invention relates to consecutive view apparatus of the kind in which a strip or band, bearing pictures of successive phases of an object in motion, is made to pass through the field of a projecting system, whereby the pictures, following each other in sufficiently rapid succession, produce the illusion or appearance of an object in motion.

The picture-bearing band or strip is usually made of celluloid or similar material, so as to be both transparent and flexible. Such materials, however, are highly inflammable, and it is difficult to arrest combustion once started therein. The source of light commonly used in the projecting apparatus is the electric arc or a refractory body raised to incandescence by a flame projected against it, and as the heat produced is considerable in both cases, it sometimes happens that the picture-bearing band is ignited. Considerable damage to the band may result, accompanied by serious injury to the adjacent apparatus. It is also a source of danger when the apparatus is used in crowded theaters or auditoriums not only from the liability of igniting nearby objects or accessories, but also on account of the alarm or panic which might be occasioned among the spectators by even a harmless blaze.

I have therefore been led to devise the present invention which has for its object to provide means for confining the burning of the band to a comparatively small section thereof, and to extinguish the fire when it would spread to other parts thereof. The ignition of the band usually occurs in the path of the projecting rays, as the heat, concentrated by one or more lenses or reflectors of the optical system, is most intense at that point, and for the reason that the carrying and feeding devices are usually

located some distance from the source of light so as to keep the greater part of the band as far from the source of heat as possible. I therefore provide devices on opposite sides of the optical axis for preventing the fire from spreading, and I illustrate herein several embodiments of this broad idea. For example, I have found that by causing the band to pass through a rather closely fitting chute or guide on each side of the optical axis, where the band crosses the projecting rays, the fire will be extinguished in the chute or chutes, and therefore will not extend beyond the small section included between the same. In fact, when the band is in use the rapid motion of the same will usually cause the ignited part to be carried into one of the chutes and there extinguished before the fire has had time to spread or do more than slight damage.

Of the invention itself, which consists of the novel features and combinations hereinafter described and more particularly pointed out in the claims, the convenient embodiment mentioned is shown in the accompanying drawing, in which—

Figure 1 is a diagrammatic side view of the preferred form, and Fig. 2 a section on line II—II, Fig. 1.

In the apparatus shown in the drawing, 1 represents a roll of the picture-bearing band or film, 2.

3 is a take-up roll, and 4, 5, sprocket over which the film passes.

6 represents a rotating device for feeding the film intermittently, and 7, 8, 9, represent lenses constituting the optical projecting system of the apparatus, projecting a beam of light from a source not shown.

The nature of the feeding devices, the projecting system, and other mechanical features of the apparatus are of course immaterial to the present invention, and may be of any convenient or suitable character.

The devices for extinguishing fire in the film are shown in Fig. 1, at 10, 11. In the embodiment here illustrated they consist of flat, open ended chutes or guides, preferably of metal, through which the film or band passes. They are preferably two in number, arranged one on each side of the path of the projecting rays, as shown in Fig. 1. In order to provide for ready insertion of

the film therein, one side, as 12, of each chute may be hinged, as shown in the detail sectional view, Fig. 2, with any suitable device to positively hold the same in closed position, as for example, a spring clasp 13.

As before stated, the function of the chute or chutes is to arrest combustion in the film. If from any cause the band should take fire, as for example, between the chutes, 10, 11, the fire will be extinguished when the same reaches, or passes into, a chute. When the band is in rapid motion the burning part would probably be drawn into the chute and the fire extinguished before the 15 band is seriously damaged, and in any case, as when the band is stationary, the fire will be extinguished by the chute or chutes when the same are reached, and therefore will not spread beyond the chute or chutes to other 20 parts of the film.

The precise way in which the combustion is arrested by the tubes or chutes does not appear to be always the same. Sometimes the extinguishing appears to be caused by 25 an action analogous to a mechanical blowing-out of the fire, as if due to a slight explosion in or at the mouth of the tube. At other times the fire appears to smolder a short distance within the tube, and then to 30 be smothered, as if by ashes, or gaseous products of combustion. These differences may be due to differences in various specimens of film used, but I have not found a film in which the combustion will not be 35 arrested. This result is quite unexpected, as it is understood that celluloid, of which the films are usually made, will, from the nature of its chemical composition, burn in a confined space, even without access of oxygen; and it is therefore probable that the 40 action here, in extinguishing the fire, is largely mechanical. The best results have been secured with chutes or tubes about three inches long and three-sixteenths of an 45 inch thick, arranged substantially horizontal, or parallel with the path of the projecting rays, but the size may of course be

varied, as well as the precise location of the parts.

What I claim is:

1. The combination with film-transmitting means and illuminating means for the film, of fire extinguishing means for said film, comprising solely a casing having an open ended passageway of sufficient size to 55 permit the free passage of the film but sufficiently constricted to extinguish the flames of a burning film that enters the same.

2. The combination with film-transmitting means, and means for illuminating the 60 film at a predetermined point, of fire extinguishing means for said film located on opposite sides of such point, said means each comprising solely a film-surrounding casing having an open-ended passageway of sufficient size to permit the free movement therethrough of the film, said passageway being 65 sufficiently constricted to extinguish the flames of a burning film that enters the same.

3. As an article of manufacture, a flame-extinguisher for picture-producing films, comprising exclusively, a fire-proof film-surrounding casing having an open-ended passageway of sufficient size to permit the 75 free movement of the film therethrough, but sufficiently constricted to automatically extinguish the flames of a burning film that extends into said passageway.

4. As an article of manufacture, a flame-extinguisher for picture-producing films, comprising solely a fireproof film-surrounding casing having an open-ended passage 80 way of sufficient size to permit the free movement of the film therethrough, but sufficiently constricted to automatically extinguish the flames of a burning film that extends into the passage way, said casing having one of its sides hinged to permit 85 ready insertion of the film.

HARRY N. MARVIN.
